EEL GRIP

Filed Sept. 1, 1932

Inventor:
Harry N. Kaiser,

Thomas W. J. Clark
Atty.

UNITED STATES PATENT OFFICE

HARRY N. KAISER, OF WASHINGTON, DISTRICT OF COLUMBIA

EEL GRIP

Application filed September 1, 1932. Serial No. 631,407.

Many fishermen believe that the eel is one of the choice varieties of fish, but they have always had difficulty in handling them after they were caught. The object of my invention is to make a holder which will make the grip on the eel perfectly secure and yet which will not injure the user.

I attain these and other objects and advantages which will appear by the pronged eel grip illustrated in the accompanying drawing, in which,

Figure 1 is a view of the grip applied to the middle finger of a hand.

Fig. 2 is a side elevation of the eel grip. Fig. 3 is an end view thereof.

Fig. 4 is a longitudinal sectional view thereof on line 4—4 of Fig. 5.

Fig. 5 is a cross-sectional view thereof substantially on line 5—5 of Fig. 4.

Similar numerals refer to similar parts throughout the several views.

The old and well known way of holding an eel is to fold the index, ring and little fingers, and with the middle finger to squeeze the eel tightly upon the back of the index and ring fingers. The eel has minute scales, deep in the skin and covered with a slippery mucous coat, and even this well known method of handling them is often not successful. My eel grip is intended to be placed on the middle finger, which should then be used in the same manner, and the grip may be placed on the right or left hand, depending on the user's choice.

The grip consists of a finger casing, in three sections, the first section 1 having a long back section projecting back over the first phalanx. The section is beaded around its end to make it easy on the finger. The second section 2 is hinged to this first section, the extending ears 3 having holes therethrough which a U shaped wire 4 is passed. This wire also passes through longitudinal slots 5 in section 1. A cap 6 extends over the back of this joint and this wire extends through it and is soldered thereto as shown by knobs 7.

Section 2 has extending ears 8 at its other end by which the section is attached to the

third section 9 of the grip by means of a similar wire 10 passing through the ears 8 and holes in section 9, the wire being soldered to section 9 as shown by knobs 11. Section 2 has a guard 12 soldered to it projecting into section 9 to prevent catching the back of the finger between the sections and to give a finished appearance to the grip.

The U shaped wires make a very inexpensive and secure means to attach the sections together. Over the inside of the front of the grip a piece of light canvas 13 or other cloth is cemented to prevent squeezing the finger between the sections, and to give the section edges a smooth contact with the finger. Sharp pointed tacks 14 are soldered to the front of the three sections. The tacks are so placed upon the sections that they will not point between the sections at the joints, when the finger is folded up. And they are likewise so spread or spaced that when the finger is folded they will not contact with each other, or interfere. The ears 3 and 8 on section 2 contact with the other two sections, in folding, thus forming stops to prevent the sections doubling upon themselves and consequently the grip will not close up tightly enough to allow the points to contact with the grip face, so they will not be dulled or pricked the user.

The sliding joint between the first and second sections allows the second section to rise up on the first, in bending, and to come back into line with it on straightening the finger. This allows greater ease in bending.

The economical, simple construction of the grip makes it practically impervious to water and the rough handling it may receive and the location of the prongs or tacks makes them very effective to grip the eel without injury to the user.

Although I have described and shown my device in an eel grip, it is apparent that the structure may be used for any other use for which it is adapted. It is likewise apparent that many details of my invention may be changed or even omitted without departing from the spirit thereof.

What I claim as new and desire to secure by Letters Patent is:

1. In an eel holder, a flexible finger member having rigid front sections over the three phalanges and prongs projecting from two or more of said front sections.
2. In an eel holder, a finger member in three sections hinged together to correspond to the joints of a finger and prongs projecting from the front of all three sections.
3. In an eel holder, a sectional finger member jointed to correspond to the joints of a finger, the joints having stops to prevent the sections doubling upon themselves and having plates over the front of the phalanges and prongs projecting from one or more of said plates.
4. In an eel holder, a sectioned finger member hinged at the sides to correspond to the joints of a finger, the hinges having stops to prevent the sections doubling upon themselves and having plates over the front of the phalanges and prongs rigidly attached to and projecting from one or more of said plates.
5. In an eel holder, a finger sheath jointed at the sides to correspond to the joints of a finger, the joint between the first and second sections being both sliding and pivotal, and prongs projecting from the front of the sheath.

HARRY N. KAISER.
